CAR COUPLER

Arthur J. Bazeley, Cleveland, Ohio, assignor to
National Malleable and Steel Castings Company,
Cleveland, Ohio, a corporation of Ohio

Application June 20, 1928. Serial No. 286,863

8 Claims. (Cl. 213—100)

My invention relates to improvements in couplers of the vertical plane, rigid jawed type, and particularly to means for preventing the couplers from becoming accidentally unlocked during buffing, and to a novel lock-setting mechanism. I have found that with couplers of the foregoing type the lock-set mechanism is sometimes unreliable due to the amount of friction which must be overcome between the faces of 5 the opposing locks as well as between the lock and coupler head of that coupler, which is in lock-set position. To obviate this difficulty I have provided a separate lock-set member which is arranged to be projected into the path of the 10 lock so as to hold it in a retracted or lock-set position and which is tripped or removed from the lock-set position by means of the opposing coupler. My invention also comprises various 15 features which I shall hereinafter describe and 20 claim.

In the accompanying drawings Fig. 1 is a side elevation of a pair of coupler heads embodying my invention; Fig. 2 is a plan, partly in section, showing a pair of opposing coupler heads embodying my invention, with the lock of one of the couplers in lock-set position; Fig. 3 is a plan, partly in section, similar to Fig. 2 but showing the position of the lock and lock-setting member as the cars draw apart; Fig. 4 is a plan, 25 partly in section, of one of the coupler heads showing the lock in locked position, which is also the position normally occupied after uncoupling has been effected; Fig. 5 is a partial section on line V—V of Fig. 2; Fig. 6 is a section 30 similar to Fig. 5 but with the lock in locked position and the lock-set member held out of operation; and Fig. 7 is a side elevation of the lock-setting member with its mounting in the buffing jaw of the coupler indicated in dotted 35 lines.

Referring more particularly to the drawings, in which I have shown a coupler head of the type described in Willison Patent No. 1,614,512, dated January 18, 1927, the coupler heads A and B are provided with the usual pulling and 40 buffing jaws 2 and 3 and with the locks 4, which are mounted and reciprocate in cavities 5 in the coupler heads and are operated by the usual actuating mechanism 6. Mounted in a recess 7 with an opening 8 on the inner face of the buffing jaw 3 is a lock-set member 9 which has fulcrum shoulders or trunnions 10 which engage 45 cooperating shoulders 11 in the recess 7. The shoulders 11 may be inclined as shown in Fig. 5 so as to center the lock-set member 9 and prevent 50 an undue amount of friction between its sides and the walls of the recess 7 and thus allow the lock-set member 9 to fall freely into its lock-setting position shown in Figs. 2 and 55 5. This action is accomplished by having the center

of gravity of the member 9 to the right of trunnions 10 as viewed in Fig. 6, so that it is overbalanced and normally tends to rotate toward the center line of the coupler head upon its trunnions 10. Below the trunnions 10 the member 9 has a depending portion or trigger 13 65 which projects outwardly through the bottom of the recess 7 in the buffing jaw 3, the outer face of which is cut back at 14 so as to give access to and permit the position of the trigger 70 13 to be observed readily by a trainman.

The forward vertically disposed face of the lock 4 on the side toward the buffing jaw 3 preferably has a recess 15 having a surface 16 normal to the line of draft and a surface 17 inclined 75 longitudinally thereto which cooperate with the surfaces 18 and 19, respectively, on the rear face and inner side face of the head 12 of the lock-setting member.

After the lock-set member 9 has been inserted 80 into the lock-set recess 7 and the lock 4 put into position in the coupler cavity 5, the lock-set member 9 cannot be removed from the buffing jaw 3, for the reason that the lock cannot be retracted far enough so as not to obstruct the 85 opening 8, into which the member 9 is inserted and removed. Hence, the lock-set member, which is designed to be readily inserted into its recess 7 before the lock is placed in position, cannot possibly be removed or lost without dis- 90 assembly of the coupler.

I prefer to arrange the lock so that in its locked or lowermost position its forward face is slightly to the rear of the forward face 20 of the buffing jaw 3, so that when in coupled position there will be clearance between the front face of the lock and the buffing face 21 of the 95 opposing coupler.

The operation of the lock-setting mechanism is as follows: With the couplers coupled and in 100 locked position, if it is desired to place one of the couplers in lock-set position the actuating mechanism 6 is operated to retract the lock. This permits the head 12 of the lock-setting member to rotate upon its trunnions 10 until the head 12 projects laterally into the path of the lock 4. As soon as the actuating mechanism 6 is released the lock 4 will slide down, bringing its face 16 to bear against the face 18 on the lock-setting member, which is normal to the 105 line of draft, and with its inclined face 17 against a similarly inclined face 19 on the projecting side of the head 12 of the lock-setting member, and the lock is thus held in lock-set position, as is shown in Fig. 2. As the cars are 110 drawn apart, one or both of the coupler heads moves laterally, thus bringing the lock of the opposing coupler B, which is still in locked position, into contact with the projecting face 19 of the lock-set head 12. This causes the lock- 115 120

setting member to rotate upon its trunnions 10 and forces the head 12 into the recess 7 and the dis-engagement of its faces 18 and 19 from the corresponding faces 16 and 17 on the lock, 5 as is shown in Fig. 3. The lock 4 will then engage the inclined surface 19 on the head 12 and as it slides down, will force the head 12 completely into the recess 7 in the buffering jaw. As is shown in Fig. 4, the lock will then slide 10 down until the lowermost or locked position is reached, and the lock-setting member will be held by the lock 4 in its recess in the buffering jaw 3. When two couplers with their respective locks in such lower-most position come together, 15 the locks move back only part way and thus do not allow the lock-set members to project into the path of the lock and the locks do not go into lock-set position.

As couplers are sometimes left by uncoupling 20 operations with the locks in lock-set position, it is obvious that if two such couplers come together coupling will not be effected. As this condition cannot be readily determined with 25 couplers of the type described which have heretofore been in use, this has resulted in delays in coupling and sometimes in the parting of trains. With my improved construction, however, the position of the trigger 13 may be 30 readily observed by the trainman, because the trigger 13 of the lock-setting member, as is shown in Figs. 1 and 5, will project outwardly in such manner that the trainman from the side of the train may see that it is in lock-set 35 position and by simply pushing inwardly upon it will retract it into its recess 7 and cause the lock to drop to its normal operating or lower-most position.

The terms and expressions which I have employed are used as terms of description and not of limitation, and I have no intention, in the use of such terms and expressions, of excluding any mechanical equivalents of the features shown and described, or portions thereof, but 40 recognize that various structural modifications are possible within the scope of the invention claimed.

What I claim is:

1. In a car coupler, a reciprocating lock, a 50 lock-setting member having a trunnion bearing in the coupler head and an overbalanced head, whereby the said member normally tends to occupy a position of lock-set engagement with the lock, said member being held out of such 55 position by engagement with a portion of the lock when the latter is in locked position.

2. In a car coupler, a reciprocating lock, a lock-setting member seating in a recess in the coupler and normally urged by gravity to a 60 projected position in front of the lock, said lock normally engaging said lock-set member and holding it in non-operating position except when the lock is operated by its uncoupling mechanism.

3. A rigid jawed coupler having jaws and a reciprocating lock arranged to engage respectively the jaws and lock of a similar coupler for 65 maintaining the couplers in intercoupler relation, and lock-setting means comprising a member mounted on the first mentioned coupler for movement by its own weight transversely of the

first mentioned lock when the lock is in retracted position and engageable with said lock to hold the latter in retracted position.

4. A rigid jawed coupler having jaws and a reciprocating lock arranged to engage respectively the jaws and lock of a similar coupler for maintaining the couplers in intercoupled relation, lock-setting means mounted on the first mentioned coupler adapted to be projected into the path of the first mentioned lock when the latter is in retracted position and to hold said lock in retracted position, the said means lying in the path of movement of a part of an opposing coupler when said couplers are disengaging from one another and being forced out of the path of said lock by said part of said opposing coupler.

5. A rigid jawed coupler having jaws and a reciprocating lock arranged to engage respectively the jaws and lock of a similar coupler for maintaining the couplers in intercoupled relation, and lock-setting means mounted on the first mentioned coupler for movement transversely of the first mentioned lock when the lock is in retracted position and engageable with 100 said lock to hold the latter in retracted position until said lock-setting means is moved by means on said similar coupler to lock-releasing position.

6. A rigid jawed coupler having jaws and a reciprocating lock arranged to engage respectively the jaws and lock of a similar coupler for maintaining the couplers in intercoupled relation, lock-setting means mounted in the first mentioned coupler for movement transversely 110 of the first mentioned lock by gravity into the path of the lock when the lock is in retracted position, and engageable with said lock to hold it in retracted position, the said lock-setting means being self-contained in the coupler and 115 requiring actuation by means separate from said first mentioned lock before the latter can be released.

7. A rigid jawed coupler having jaws and a reciprocating lock arranged to engage respectively the jaws and lock of a similar coupler for maintaining the couplers in interengaged relation, a lock-setting member so mounted in a recess in a jaw of the first mentioned coupler that a plane extending transversely through the 125 interengaging portions of the couplers passes through said member, said member being adapted to be projected into the path of the first mentioned lock when the latter is in retracted position and to hold said lock in retracted position, said member having trunnion bearing 130 upon which it is rotated into and out of lock-setting position.

8. A rigid jawed coupler having jaws and a reciprocating lock arranged to engage respectively the jaws and lock of a similar coupler for maintaining the couplers in intercoupled relation, a lock-setting member mounted in a recess in a jaw of the first mentioned coupler for movement into the path of movement of the 140 lock of an opposing coupler when said first named lock is in retracted position, and engageable with said first named lock to hold the latter in retracted position.

ARTHUR J. BAZELEY. 145
